Primary Examiner — David G Muller*Assistant Examiner* — Nathan M Johnston(74) *Attorney, Agent, or Firm* — Knobbe Martens Olson
& Bear, LLP; Robert M. Hupe(57) **CLAIM**

The ornamental design for a stackable cantilever chair frame, as shown and described.

DESCRIPTION

FIG. 1 is a front, top, right side perspective view of the stackable cantilever chair frame showing my new design.

FIG. 2 is a front, bottom, right side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The design is directed to a frame that forms a lower portion of a stackable cantilever chair. The broken line showing of parts of the drawings is included for the purpose of illustrating use and environment and forms no part of the claimed design.
